REVERSIBLE ENGINE CONTROL APPARATUS

Roy R. Stevens, Forest Hills, and Raymond E. Miller, Wilkinsburg, Pa., assignors to The Westinghouse Air Brake Company, Wilmerding, Pa., a corporation of Pennsylvania

Application March 29, 1949, Serial No. 84,174

5 Claims. (Cl. 60—16)

1

This invention relates to engine control apparatus and more particularly to fluid pressure control apparatus for controlling the starting, stopping, running and reversing of such as a reversible Diesel engine.

The principal object of the invention is the provision of a relatively simple engine control apparatus for remotely controlling operation of a Diesel engine.

Other objects and advantages will hereinafter be apparent from the following more detailed description of the invention.

In the accompanying drawing, Fig. 1 is a schematic representation, partly in outline and partly in section, of fluid pressure control apparatus embodying the invention; Fig. 2 is a cross-sectional view in detail of a relay valve device, several of which are shown symbolically in the apparatus shown in Fig. 1; Fig. 3 is a cross-sectional view of a double check valve device shown in outline in the apparatus shown in Fig. 1, and Fig. 4 is a cross-sectional view in detail of a reducing valve device, several of which are shown symbolically in Fig. 1.

Description

In the drawing, the reference numeral 1 refers to a portion of one end of a crank shaft of a reversible Diesel engine which may be of the two cycle or four cycle type, and reference numeral 2 refers to a reversing shaft for said engine, which, in the case of a four cycle engine may be operatively connected to the engine cam shaft for shifting said shaft to one position or another to permit the engine to be started by compressed air for operation in either direction of operation to, for example, drive a ship ahead or astern. In the case of a two cycle engine, the engine reversing shaft 2 may be operatively connected to a starting air distributor on the engine which may be conditioned in one rotary position of shaft 2 to so distribute supply of starting air to the engine cylinders as to cause the engine to turn over in its one or ahead direction and which may be conditioned in an opposite rotary position of shaft 2 to so distribute supply of starting air to the engine cylinders as to cause the engine to turn over in its opposite or astern direction. A reversing lever 3 is attached to the shaft 2 to act as a medium through which said shaft may be positioned. "Ahead" and "astern" positions of lever 3 and shaft 2 are indicated in the drawing by dot-and-dash lines appropriately titled.

The reference numeral 4 refers to a governor speed control shaft which is rockable through

5 a governor speed control lever 4' to different angular positions to regulate the speed setting of a speed governor device (not shown) accordingly. By rocking movement of the control shaft 4 to and between an "idling speed" and "full speed" positions, indicated in the drawing by dot-and-dash lines so titled, the speed setting of the governor device may be adjusted accordingly to call for a minimum engine speed corresponding to the "idling speed" position of shaft 4 up to a maximum engine speed corresponding to its "full speed" position. In the well-known manner, the governor device, which is arranged to be driven by the engine, will operate to maintain speed of the engine substantially constant and in accord with the governor speed setting by regulating the amount of fuel supplied to said engine. Reference numeral 5 refers to a fuel control shaft which may be operably connected to the speed governor device in the well-known manner by means (not shown), and operatively connected to flow regulating means (not shown) for controlling the amount of fuel to be supplied to the engine. The shaft 5 is rockable by the governor device through a connection (not shown) to various angular positions to and between limit positions indicated in the drawing by dot-and-dash lines bearing titles, "fuel off" and "full fuel," respectively, to regulate the fuel supply to the engine accordingly. The usual governor device, whose speed setting always calls for operation of the engine at least at an idling speed, cannot be set to actuate the fuel control shaft 5 to its "fuel off" position for stopping the engine to terminate its operation or preparatory to reversing, so that a fuel cut-off cylinder device 6 is provided which is operative to act through the medium of a lever 7 and overcome action of the governor device to push the fuel control shaft 5 to its "fuel off" position for cutting off supply of fuel to the engine. The fuel cut-off cylinder device 6, at termination of its operation, is so conditioned as not to interfere with positioning of the fuel control shaft 5 by the governor device, as will be described in detail hereinafter.

The reference numeral 11 refers to a fluid pressure reversing motor for actuating the reversing shaft 2 to its two different positions, and reference numeral 12 refers to a speed control cylinder device for adjusting position of the speed control lever 4' and thereby shaft 4. Reference numeral 15 refers to an engine starting air valve device for controlling supply of starting air to the engine. Reference numeral 16 refers to a re-

lay valve device for controlling operation of the fuel cut-off cylinder device 6. Reference numeral 17 refers to a directional interlock device arranged to cooperate with relay valve device 16 for controlling operation of the fuel cut-off cylinder device 6. Reference numeral 18 refers to a relay valve device for controlling operation of the starting air valve device 15. Reference numeral 19 refers to a relay valve device for controlling selection of one or another of two fluid supply pressures for reasons which will be set forth hereinafter. Reference numerals 20 and 21 refer to two reducing valve devices which are so arranged as to make the above-mentioned two supply pressures available from a common source at a third and higher pressure such as a reservoir 22. Reference numeral 23 refers to a double check valve device which modifies operation of relay valve devices 16 and 18. Reference numeral 26 refers to an operator's control valve device which is arranged to control operation of the entire apparatus, as will be described hereinafter.

The fuel cut-off cylinder device 6 is shown schematically in the drawing, and for sake of illustration may simply comprise a casing containing a piston 30 having a piston rod 31 attached thereto which extends slidably through one end of the casing for contact with the lever 7. At one side of piston 30 there is a pressure chamber 32 which is adapted to be supplied with fluid under pressure by way of a pipe 33, while at the opposite side of said piston there is a spring chamber 34 which contains a compression spring 35 arranged to urge the piston 30 in the direction of chamber 32. The fuel cut-off cylinder device 6 is so adapted and arranged relative to the fuel control lever 7 that with supply of fluid under pressure to chamber 32 the piston 30 will overcome action of spring 35 and move the rod 31 into contact with said lever 7 and cause same to assume its "fuel off" position. Upon subsequent release of fluid under pressure from the chamber 32, the spring 35 will move piston 30 and rod 31 to a position in which lever 7 has full freedom of movement between its "fuel off" and "full fuel" positions without interference from said rod.

The fluid pressure reversing motor 11 may comprise a casing containing a reversing piston 40 having a piston rod 41 which extends slidably through the casing and has an operative connection with the reversing lever 3 through the medium of a pin connected link 42. At one side of piston 40 there is a pressure chamber 43 which is adapted to be supplied with fluid under pressure by way of an ahead control pipe 44 for causing said piston to move in the direction of an opposite chamber 45 to move the reversing shaft 3 to its "ahead" position in which it is shown in the drawing. The chamber 45 is adapted to be supplied with fluid under pressure by way of an astern control pipe 46 for causing piston 40 to move in the direction of chamber 43 and acting through rod 41, to thereby move the reversing lever 3 to its "astern" position opposite to that in which it is shown in the drawing. When fluid under pressure is supplied to one of chambers 43 or 45 for causing movement of the piston 40 as above, the other of said chambers will be vented to atmosphere to allow for such movement, as will be described hereinafter.

The speed control cylinder device 12 schematically may be substantially similar to the fuel cut-off cylinder device 6 and may simply comprise a cylinder in which is slidably disposed a piston 50 having an operative connection with

the speed control lever 4' through the medium of a piston rod 51 and a pin connected link 52. At one side of piston 50 there is a pressure chamber 53 which is adapted to be supplied with fluid under pressure by way of a speed control pipe 54, while at the opposite side of said piston there is a spring chamber 55 in which is disposed a compression spring 56, which is arranged to oppose movement of said piston in the direction of the spring chamber. With pressure of fluid in the chamber 53 at a minimum pressure, which pressure may be atmospheric pressure, piston 50 will assume the position in which it is shown in the drawing with the speed control lever 4' disposed in its "idling speed" position. Upon supply of fluid to chamber 53 at a maximum pressure which may be thirty pounds, for example, piston 50 will overcome action of spring 56 and move to an extreme position opposite to that in which it is shown in the drawing, to cause the speed control lever 4' to assume its "full speed" position. Piston 50, hence speed control lever 4' may be caused to assume any position intermediate their corresponding extreme limit positions by adjustment of the pressure of fluid in the chamber 53 between atmospheric pressure and thirty pounds, for example.

The starting air valve device 15 and the relay valve devices 16, 18 and 19 for sake of illustration, schematically may be alike. Referring to Fig. 2, each of the above mentioned devices may comprise a casing 100 having a diaphragm 101 disposed therein and subject to pressure of fluid in a diaphragm control chamber 102 on its one side and to pressure of fluid in a chamber 103 on its opposite side. Also formed in the casing are chambers 104, 105 and 106, chamber 104 being separated from the chamber 103 by a partition 107 and from the chamber 105 by a partition 108. A partition 109 separates the chamber 105 from the chamber 106. A valve 110 is disposed in the chamber 104 for controlling communication between the chamber 105 and said chamber 104. The valve 110 may be secured to a fluted stem 111 slidably mounted in a suitable bore extending through the partition 108, a valve seat being formed at the end of the bore opening into the chamber 104 to accommodate the valve 110. A valve 112, similar to the valve 110, is disposed in the chamber 106 for controlling communication between the chamber 105 and said chamber 106. The valve 112 is attached to a fluted stem 113 which is slidably disposed in a suitable bore extending through the partition 109, a valve seat being formed in the end of said bore opening into the chamber 106 to accommodate the valve 112. Both of the fluted stems 111 and 113 project into and meet in the chamber 105. A bias spring 114 is disposed in the chamber 106 and arranged to urge the valve 112 toward its seat and, at the same time, through engagement of stems 111 and 113, to urge the valve 110 away from its seat. The valve 110 is operably connected to the diaphragm 101 by means of a rod or stem 115 extending through a bore in the partition 107. A control spring 116 is provided in chamber 103 to oppose deflection of the diaphragm 101 in the direction of the chamber 103.

In operation of the valve device shown in Fig. 2, with the chamber 103 open to atmosphere, upon supply of fluid under a pressure sufficient to overcome action of the control spring 116, the diaphragm 101 will deflect in the direction of the chamber 103 and against action of the bias spring

114 will cause seating of the valve 110 and unseating of the valve 112. With valve 110 closed and the valve 112 open, chamber 105 will be closed to the chamber 104 and open to the chamber 106. Upon subsequent reduction in pressure of fluid below a certain value as determined by compression of spring 116, the bias spring 114 and the control spring 116 will return to diaphragm 101 and the valves 110 and 112 to the position in which they are shown in the drawing, the valve 112 being seated and the valve 110 being unseated. With the valve 110 being unseated and the valve 112 seated, the chamber 105 will be closed to the chamber 106 and open to the chamber 104.

Hereinafter, in describing operation of any of the valve devices 15, 16, 18 or 19 which are similar to the device shown in detail in Fig. 2, when the valve 110 is unseated and the valve 112 is seated, a communication, indicated symbolically in the drawing by a solid line bearing the reference numeral 118, will be established to connect the chamber 105 to the chamber 104. Similarly, when the valve 110 is seated and the valve 112 unseated, a communication, indicated in the drawing symbolically by a dash line bearing the reference numeral 119, will be established to connect the chamber 105 to the chamber 106. When one of the communications 118 or 119 is established, the other of said communications simultaneously will be disestablished.

The directional interlock device 17 may be substantially like that disclosed and described in detail in the United States Patent No. 2,459,883 of Cecil S. Kelley issued January 25, 1949.

Since reference may be made to the above Kelley patent for a detailed description of the directional interlock device 17, only a brief operational description thereof is included in the present application. Briefly, therefore, the directional interlock device 17 is operable in response to supply of fluid under pressure to a pipe 240 to sense the direction of rotation of the engine crank shaft 1, through actuation of a retractable shoe 241 into engagement with said shaft, and to establish communication between one or the other of the ahead and astern control pipes 44, 46 and a pipe 244 according to direction of such rotation, and to maintain such connection when fluid under pressure is subsequently vented from the pipe 240, with resultant retraction of the shoe 241 away from the shaft 1. If the engine crank shaft 1 is turning in its ahead direction when the shoe 241 is caused to engage said shaft, the directional interlock device 17 will respond to assume what will hereinafter be referred to as its ahead position in which the astern control pipe 46 is connected to the pipe 244 and the latter pipe is disconnected from the ahead control pipe 44. Conversely, if the shaft 1 is rotating in its opposite or astern direction at the time that the shoe 241 is in engagement with said shaft, the directional interlock device 17 will assume what will herein-after be referred to as its astern position in which the pipe 244 will be disconnected from the astern control pipe 46 and will be connected to the ahead control pipe 44. If, at the time that shoe 241 is caused to engage shaft 1, said shaft is not rotating, the interlock device 17 will remain in whichever of its two positions it last assumed during a previous engagement of said shoe with said shaft when rotating.

Referring to Fig. 4, the reducing valve devices 20 and 21 each may comprise a casing 66 having

therein a supply chamber 67, a delivery chamber 68, a control chamber 69 and an exhaust chamber 70. A movable valve seat element 71 is arranged for movement by a stem 65 and is adapted to cooperate with a supply valve 72 for controlling communication between the supply chamber 67 and the delivery chamber 68. The supply valve 72 may be in the form of a ball disposed within a cavity 73 formed in the seat element 71. The cavity 73 may be open by way of ports 74 in one end to the supply chamber 67 and by way of a central opening 75 in its opposite end to the delivery chamber 68. A seat may be formed in one end of opening 75 against which supply valve 72 may seat to close off cavity 73, hence supply chamber 67, from delivery chamber 68. A bias spring 76 may be disposed in the cavity 73 and arranged to urge the supply valve 72 toward its seated position. The stem 65 may have a screw-threaded attachment with the casing 66 and be provided with a knurled knob 77, or the like, disposed outside the casing for manual adjustment of position of said stem. Thus the seat element 71 may be moved in the direction of chamber 68 or in the opposite direction by adjustment of stem 65. A release valve seat element 78, secured for movement with deflection of a flexible diaphragm 79, is provided for accommodating a release valve 80 which is disposed in the delivery chamber 68. Diaphragm 79 forms a partition within the casing and divides the control chamber 69 from the exhaust chamber 70. The control chamber 69 is constantly open to the delivery chamber 68 by way of a choke 81 while the exhaust chamber 70 is constantly open to the atmosphere by way of a port 82 in the casing. Diaphragm 79, therefore, is subject opposingly to delivery pressure of fluid in the chamber 68 on one side and to atmospheric pressure in the chamber 70 on its opposite side. The release valve seat element 78 forms a movable partition between the delivery chamber 68 and the control chamber 69 and prevents direct impingement of fluid under pressure on the diaphragm 79 as same is supplied to said delivery chamber. Choke 81 prevents any sudden pressure impulses which may occur in the chamber 68 from influencing diaphragm deflection. The release valve seat element 78 comprises a portion 83 which extends through a control opening in the diaphragm 79 and into the exhaust chamber 70. A nut 84 is in screw-threaded attachment with portion 83 for securing element 78 to the diaphragm. A control opening 85 extends from the chamber 68 at one end of the element 83 to its opposite end, opening into the exhaust chamber 70. A valve seat may be formed at one end of the opening 85 on which the release valve 80 may seat for closing off the delivery chamber 68 from the exhaust chamber 70 via said opening. Release valve 80 is rigidly secured to the supply valve 72 by means of a small rod 86. A bias spring 87 may be provided for urging the seat element 71 to follow movement of the stem 65. A compression control spring 88 is disposed in the exhaust chamber 70 and arranged to act on the diaphragm 79 to oppose action of pressure of fluid in the control chamber 69 on said diaphragm. One end of the spring 88 abuts a spring seat element 89 carried by a screw-threaded shaft 90 which is adjustable manually to change the pre-compression of the spring 88 as may be desired to suit operating conditions of the reducing valve device.

In the reducing valve device 21, its supply cham-

ber 67 is connected to the reservoir 22 by way of such as a supply pipe 300 and its delivery chamber 68 is connected to a pipe 301. The pressure of fluid in the reservoir 22, hence in the chamber 67, may be about two hundred and fifty pounds, for example, to act as a source of starting air at pressure adequate to turn the engine over during starting.

In the reducing valve device 20, its supply chamber 67 is connected to the pipe 301 and its delivery chamber 68 is connected to a pipe 302.

In operation of each of the reducing valve devices 20 and 21, with the supply chamber 67 charged with fluid at a certain pressure, the knob 77 may be turned to advance the stem 65 inwardly of the casing and thereby move the seat element 71 in the direction of the chamber 68 for unseating the supply valve 72 which is restrained from such movement by engagement of the release valve 80 with the seat element 78 which is at this time stationary. This adjustment of knob 77 may be done initially in setting up the apparatus to allow fluid under pressure from the supply chamber 67 to flow by way of the unseated supply valve 72, the opening 75 in seat element 71, the delivery chamber 68. Pressure of fluid thus supplied to the delivery chamber 68 will be realized in the control chamber 69 by way of the choke 81. When the pressure of fluid in the control chamber 69 acting on the diaphragm 79 increases sufficiently to overcome the initial compression of the control spring 88, said diaphragm will deflect in the direction of the exhaust chamber 70 against opposing action of said spring. This deflection of the diaphragm will carry with it the release valve seat element 78. By action of the spring 76 in the seat element 71, the release valve 80 will remain seated on the seat element 78 and will follow movement thereof, as will the attached supply valve 72, which movement will advance the supply valve toward its seat on said element 71. When the supply valve 72 reseats on the element 71, and thus closes off the supply chamber 67 from the delivery chamber 68, further increase in pressure of fluid in said delivery chamber is thereby prevented. The degree of pressure which may be established in the delivery chamber 68 will depend upon the distance the supply valve must travel to reseat and upon the initial compression of the spring 88. For a given compression of spring 88, the pressure of fluid in the delivery chamber 68 may be increased in direct proportion to the distance that the seat in seat element 71 is disposed away from the supply valve 72, as determined by adjusted position of the stem 65.

The reducing valve device is operative automatically to maintain fluid in its delivery chamber at the pressure for which it is set. For example, should pressure of fluid in the delivery chamber 68 tend to increase above the value for which it is set, such increase in pressure in the control chamber 69, connected to the chamber 68, acting on the diaphragm 79 will deflect same downwardly, pulling seat element 78 away from the release valve 80, allowing the excess pressure of fluid in the delivery chamber to be reduced by flow of fluid therefrom by way of the opening 85, exhaust chamber 70 and the port 82. When the desired value of pressure of fluid in the delivery chamber 68 is thus again reestablished, through consequent upward deflection of the diaphragm, the seat element 78 again will contact the release valve 80, closing off said de-

livery chamber from the exhaust chamber to maintain the desired pressure.

By proper adjustment of its stems 65 and 90, the reducing valve device 21 may be set to maintain a pressure of one hundred pounds, for example, in the pipe 301. Similarly, the reducing valve device 20 may be set to maintain a pressure such as thirty pounds in the pipe 302.

The reservoir 22 may store fluid at some such pressure as two hundred and fifty pounds for supply to the engine in starting, as will be described hereinafter. The reducing valve device 21 may reduce fluid from a reservoir pipe 300 at two hundred fifty pounds to a supply pipe 301 at pressure of one hundred pounds for example, for employment in the control apparatus, as will be described hereinafter. Also, the reducing valve device 20 will reduce the pressure of fluid in the pipe 301 for delivery to a supply pipe 302 at a pressure of thirty pounds, for example, for employment in the control apparatus as will be shown.

Referring to Fig. 3, the double check valve device 23, for sake of illustration may comprise a casing 200 having a bore 201 extending longitudinally therethrough. One end of the bore 201 may be closed by an end member 202 suitably secured to the casing 200 by means not shown, and the opposite end of said bore may be closed by an end member 203 similar to member 202. Resilient seat members 204 and 205 may be clamped between the casing 200 and the members 202 and 203, respectively, at opposite ends of the bore 201 for seating and sealing engagement with a piston valve element 206 which is slidably disposed in said bore. One inlet opening 207 to the double check valve device 23 may extend through the end member 202 and seat member 204 into one end of the bore 201, while another inlet opening 208 may extend through the end member 203 and seat member 205 into the opposite end of said bore. The length of the piston valve element 206 is considerably less than the length of the casing 200, and when fluid under pressure is supplied to the inlet opening 207 when opening 208 is vented to atmosphere, said piston element will assume a position seated on seat member 205. Conversely when fluid under pressure is supplied to the inlet opening 208 with opening 207 vented to atmosphere, the piston valve element 206 will assume the position in which it is shown in the drawing, seated against the seat member 204. Intermediate opposite ends of the bore 201, the double check valve device is provided with an outlet opening 209 which opens radially into said bore. When the piston valve element 206 is in the position in which it is shown in the drawing, the outlet opening 209 is closed to the inlet opening 207 and is open to the inlet opening 208 by way of the bore 201. Conversely, when the piston valve element 206 is caused to assume its opposite position seated on seat member 205, the outlet opening 209 is closed to the inlet opening 208 and is open to the inlet opening 207 by way of the bore 201.

The operator's control device 26 may be similar to that shown and described in detail in United States Patent No. 2,413,390, issued to Roy R. Stevens, December 31, 1946, and assigned to the assignee of the present application. For detailed description of the control device 26, therefore, reference may be made to the above patent.

Briefly, the operator's valve device 26 comprises valve means (not shown) for controlling selective

establishment and disestablishment of connections between a control supply pipe 400 and the ahead and astern control pipes 44, 46 as well as a start control pipe 401, and for effecting variations in pressure of fluid in the speed control pipe 54. An operator's control lever 402 is provided for controlling operation of the valve means.

The lever 402 extends through a guide slot 403 and has a "stop" position intermediate the ends of said slot. At one side of "stop" position, which side is indicated in the drawing by a legend "ahead," the lever 402 has a "run and idle" position which is located substantially midway between "stop" position and one end of the slot 403 where said lever has a "full speed" position. Adjacent to the "run and idle" position, the slot 403 opens to a transverse slot 404 to allow for movement of lever 402 to a "start" position. At the opposite side of "stop" position, indicated by the legend "astern," the lever 402 has oppositely arranged corresponding "run and idle" and "full speed" positions and a similar "start" position disposed opposite to "run and idle" position in a slot 405.

In "stop" position of lever 402, the valve means (not shown) controlled by said lever are positioned to open the ahead, astern, speed, and start control pipes 44, 46, 54 and 401, respectively, to atmosphere. In "run and idle" position at the "ahead" side of "stop" position, the valve means controlled by lever 402 are conditioned to connect the ahead control pipe 44 to the control supply pipe 400 while maintaining the astern control pipe 46, the speed control pipe 54 and the start control pipe 401 vented to atmosphere. By moving lever 402 into slot 404, the start control pipe 401 is also connected to the control supply pipe 400 along with the ahead control pipe 44. In "run and idle" position of lever 402 at the opposite or "astern" side of "stop" position, the astern control pipe 46 is connected to the control supply pipe 400, while the ahead control pipe, the speed control pipe 54 and the start control pipe 401 are vented to atmosphere. Upon movement of the lever 402 into the slot 405, the start control pipe 401 is connected to the control supply pipe 400 along with the astern control pipe 46.

When the lever 402 is in either of the "run and idle" positions, the speed control pipe 46 is open to atmosphere as above mentioned, for rendering the speed control cylinder device 12 effective to maintain the governor speed control lever 4' in its "idling speed" position in which it is shown in the drawing, while upon movement of the operator's control lever 402 to either of the "full speed" positions, fluid at a maximum degree of pressure is provided in the speed control pipe 54 for rendering the speed control cylinder device 12 effective to move the governor speed control lever 4' to "full speed" position to thereby provide for operation of the engine at maximum speed. Any desired speed setting of the governor device may be effected through positioning of lever 4' by suitable adjustment of the operator's control lever 402 between either of the "run and idle" positions and the corresponding "full speed" position.

While the lever 402 is being positioned within the range between "run and idle" and "full speed" on the "ahead" side of "stop" position, the ahead control pipe 44 will remain connected to the control supply pipe 400, and conversely, while said lever is positioned within the opposite corresponding range on the "astern" side, the astern con-

trol pipe 46 will remain connected to said control supply pipe.

In the double check valve device 23, its inlet opening 207 is connected to a branch of the ahead control pipe 44, its inlet opening 208 is connected to a branch of the astern control pipe 46 and its outlet opening 209 is connected to the respective control chambers 102 in the relay valve devices 16 and 18 by way of a pipe 500.

10 In the relay valve device 16, its chamber 104 is connected to the one hundred pound supply pipe 301, its chamber 105 is connected to the pipe 240, and its chamber 106 is connected to the pipe 244.

15 In the relay valve device 18, its chamber 104 is connected to atmosphere by way of such as a pipe 501, its chamber 105 is connected to the pipe 240, and its chamber 106 is connected to the one hundred pound supply pipe 301.

20 In the relay valve device 19, its chamber 104 is connected to the thirty pound supply pipe 302, its chamber 105 is connected to the control supply pipe 400 and its chamber 106 is connected to the one hundred pound supply pipe 301.

25 In the starting air valve device 15, its chamber 104 is connected to atmosphere by way of such as a pipe 502, its chamber 105 is connected to a pipe 503 in turn connected to the engine for conveying starting air thereto, and its chamber 106 is connected to the two hundred fifty pound supply pipe 300 to act as a source of supply of starting air for turning the engine over in starting.

30 In all the devices 15, 16, 18 and 19, their respective chambers 103 are vented to atmosphere by way of such as a port 504.

Operation

Let it be assumed initially that the operator's control lever 402 is in "stop" position, in which position it is shown in the drawing, with the ahead, astern, speed and start control pipes 44, 46, 54 and 401 vented to atmosphere. Chambers 43 and 45 in the fluid pressure reversing motor 11 thus will be vented to atmosphere via the ahead and astern control pipes 44 and 46 so that the reversing piston 40 will be in a static condition, for instance in the position in which it is shown in the drawing for operation of the engine in the ahead direction in which direction it may be assumed to have been previously operating. At the same time, with both the ahead and astern control pipes 44 and 46 vented to atmosphere, the respective control chambers 102 in the relay valve devices 16 and 18 will be so vented by way of the double check valve device 23. Both of the relay valve devices 16 and 18, therefore, will be positioned establishing their respective communications 118. The pipe 33 to the fuel cut-off cylinder device 6, therefore, will be connected via relay valve device 16 to the one hundred pound supply pipe 301, so that piston 30 in device 6 will be in the position in which it is shown in the drawing, holding the fuel control lever 7 in its "fuel off" position so that no fuel will be supplied to the engine at this time. At the same time, the pipe 240 to the directional interlock device 17 will be vented to atmosphere via the relay valve device 18 and the pipe 501, so that the shoe 241 of said directional interlock device will be in its retracted position out of contact with the engine crank shaft 1 and said directional interlock device 17 will be in its last assumed, or ahead position, connecting the pipe 244 to the astern control pipe 46. Also, with the pipe 240

vented to atmosphere, the control chamber 102 in the starting air valve device 15 will be so vented, with the result that its communication 118 is established, thereby connecting the pipe 503 to atmosphere by way of the pipe 502. No starting air, therefore, is being supplied to the engine by way of pipe 503, and since neither is fuel being supplied at this time, the engine and hence crank shaft 1 will not be turning over.

With the speed control pipe 54 vented to atmosphere as aforementioned, the speed control cylinder device 12 will be in the position in which it is shown in the drawing, holding the governor speed control lever 4' in its "idling speed" position in which it also is shown in the drawing.

With the start control pipe 401 vented to atmosphere, the control chamber 102 in the relay valve device 19 will be so vented, with the result that the communication 118 of said device will be in establishment, connecting the control supply pipe 400 to the thirty pound supply pipe 302.

Now let it be assumed that the operator desires to start the engine for operation in the same, or ahead, direction in which it last operated, as determined by position of the reversing piston 40. The operator will then move the control lever 402 in the control valve device 26 out of "stop" position in the "ahead" direction in the slot 403, thereby effecting connection of the ahead control pipe 44 to the control supply pipe 400, while maintaining the astern, speed and start control pipes 46, 54 and 401 vented to atmosphere.

Since at this time the control supply pipe 400 is connected by way of the relay valve device 19 to the thirty pound supply pipe 302, fluid under pressure from the latter pipe will flow via the former pipe, through the operator's control device 26 into the ahead control pipe 44.

From the ahead control pipe 44, this fluid under pressure will flow to the chamber 43 in the fluid pressure reversing motor 11, but since said motor is already in its ahead position, the reversing piston 40 will remain static as will the reversing lever 3, conditioning the engine for operation in its ahead direction.

From the ahead control pipe 44, fluid under pressure will also flow by way of the double check valve device 23 and the pipe 500 to the respective control chambers 102 in the relay valve devices 16 and 18 where the pressure of fluid at this time will thus be increased from atmospheric to a pressure of thirty pounds.

The relay valve device 16, having a control spring 116 of the proper initial compression, will respond to pressurization of its control chamber at thirty pounds to disestablish its communication 118 and to establish its communication 119, thereby disconnecting the pipe 33 from the one hundred pound supply pipe 301 and connecting said pipe 33 to the pipe 244.

Since at this time the pipe 244 is vented to atmosphere by way of the directional interlock device 17 and the astern control pipe 46, fluid under pressure from chamber 32 in the fuel cut-off cylinder device 6 will vent to atmosphere by way of pipe 33, communication 119 in the relay valve device 16 and said pipe 244. The fuel cut-off cylinder device 6 will then respond to move the rod 31 to a position away from the fuel control lever 7 to allow the speed governor device to control supply of fuel to the engine.

The thirty pounds pressure of fluid in the control chamber 102 in the relay valve device

18 will not be sufficient to overcome action of the control spring 116 in said device 18 since the initial compression of said spring is such as will oppose such fluid until it attains a pressure of substantially sixty pounds, for example. The relay valve device 18 therefore will maintain establishment of its communication 118 at this time, so that the pipe 240 remains vented to atmosphere by way of the pipe 501. The directional interlock device 17 will remain in its ahead position with shoe 241 retracted and the control chamber 102 in the starting air valve device 15 will remain vented. The starting air valve device 15, therefore, will maintain establishment of its communication 118 connecting the pipe 503 to atmosphere.

From movement of the control lever 462 in slot 403 out of "stop" position in the "ahead" direction, the operator will move said lever to "start" position in the slot 404, thereby effecting connection of the start control pipe 401 to the control supply pipe 400 along with the ahead control pipe 44 while the astern and speed control pipes 46 and 54 remain vented to atmosphere.

Fluid under pressure from the control supply pipe 400 will then flow by way of the operator's control device 26 and the start control pipe 401 to the control chamber 102 in the relay valve device 19 wherein the fluid pressure will be increased from atmospheric to thirty pounds pressure. The pressure of thirty pounds in the control chamber of the relay valve device 19 will be sufficient to overcome action of the control spring 116 in said device which therefore will respond to disestablish its communication 118 and to establish its communication 119. The control supply pipe 400 consequently is disconnected from the thirty pound supply pipe 302 and is connected to the one hundred pound supply pipe 301.

With the control supply pipe 400 thus connected to the one hundred pound supply pipe 301, fluid under pressure will flow by way of the operator's control device 26, the ahead control pipe 44, the double check valve device 23 and the pipe 500 to the control chamber 102 in the relay valve device 18 where the pressure will thus be increased from thirty to one hundred pounds. The relay valve device 18 will then respond to such an increase in pressure of fluid in its control chamber to disestablish its communication 118 and to establish its communication 119.

The pipe 240 will then become connected to the one hundred pound supply pipe 301 by way of the communication 119 in relay valve device 18, so that fluid under pressure will flow by way of said pipe 240 to the directional interlock device 17 and to the control chamber 102 in the starting air valve device 15. The shoe 241 of the directional interlock device 17 will be brought into engagement with the engine crank shaft 1, and the starting air valve device 15 will respond to disestablish its communication 118 and to establish its communication 119, connecting the pipe 503 to the two hundred fifty pound supply pipe 300. Starting air from the pipe 300 will then flow via device 15 and pipe 503 to the engine which is thereby turned over in its ahead direction.

Since the fuel control lever 7 is free to be positioned by the speed governor device at this time, fuel will be supplied to the engine along with the starting air. When such fuel fires and causes running of the engine at idling speed, the operator may move the operator's control lever 402 from "ahead" "start" to the "ahead" "run and idle"

position, with consequent venting of the start control pipe 401 along with the astern and speed control pipes 50 and 54 while the ahead control pipe 44 is maintained connected to the control supply pipe 400.

Upon thus venting of the start control pipe 401 to atmosphere, the relay valve device 19 will disestablish its communication 118 and reestablish its communication 119, thereby disconnecting the control supply pipe 400 from the one hundred pound supply pipe 301 and again connecting said pipe 400 to the thirty pound supply pipe 302. Fluid under pressure in the control chamber 102 in the relay valve device 18 will then reduce from one hundred pounds to thirty pounds by way of the pipe 500, double check valve device 23, the ahead control pipe 44, the operator's control device 26, the control supply pipe 400, communication 118 in the relay valve device 19, supply pipe 302, and the reducing valve device 20, as will be appreciated from previous description of operation of said device 20. The relay valve device 18 will then respond to disestablish its communication 119 and to establish its communication 118, thereby again venting the pipe 240 to atmosphere by way of the pipe 501.

With the pipe 240 again vented, the shoe 241 of the directional interlock device 17 will again retract, while said device remains in its ahead position, and the starting air valve device 15 will respond to disconnect the pipe 503 from the supply pipe 300 and connect said pipe 503 to atmosphere by way of the pipe 502 by establishment of its communication 118. The supply of starting air is thus cut off as the engine continues to run at idling speed on fuel.

It will be appreciated that when pressure of fluid in the control chamber of the relay valve device 18 is increased from thirty to one hundred pounds or subsequently reduced from one hundred to thirty pounds a similar increase and a similar reduction in pressure is experienced in the corresponding control chamber in the relay valve device 16, but such changes have no effect on the position of device 16 which assumes its positions upon establishment of the thirty pound pressure and reduction substantially below the thirty pound pressure.

With the engine thus running on fuel, the operator may regulate the speed of its operation by proper adjustment of position of lever 402 in the slot 403 intermediate "ahead" "run and idle" position and "ahead" "full speed" position, as will be appreciated from previous description.

From the above description, it will be seen that restarting the engine in the last direction of operation consists essentially in effecting supply of fluid under pressure to the relay valve device 16 for releasing the fuel cut-off cylinder device 6 and to the relay valve device 18 for causing starting air to be supplied to said engine, and upon running of same on fuel, to effect the proper reduction in pressure in the relay valve device 18 to cause termination of such supply of starting air.

When the operator desires to stop the engine while thus running in its ahead direction, he will move the control lever 402 in slot 403 back to "stop" position, thereby again venting the ahead and speed control pipes 44 and 54 along with the astern and start control pipes 46 and 401 to atmosphere.

With the ahead control pipe 44 thus vented to atmosphere, the fluid at thirty pounds pressure will release to atmosphere from the respective control chambers 102 in the relay valve devices

16 and 18 by way of the pipe 500, the double check valve device 23, and said ahead control pipe.

Such a reduction in pressure of fluid from thirty pounds to atmospheric will not influence the position of the relay valve device 18, which will maintain establishment of its communication 118, as will be appreciated from previous description.

Reduction in pressure of fluid in the control chamber of relay valve device 16 from thirty pounds to atmospheric, however, will render said relay valve device responsive to disestablish its communication 119 and to establish its communication 118, thereby disconnecting the pipe 33 from the pipe 244 and connecting said pipe 33 to the one hundred pound supply pipe 301. Fluid under pressure will then flow from the pipe 301 by way of the relay valve device 16 and the pipe 33 to the chamber 32 in the fuel cut-off cylinder device 6. The fuel cut-off cylinder device 6 will then respond to assume the position in which it is shown in the drawing, overcoming the action of the speed governor device and holding the fuel control lever 7 in its "fuel off" position. With the fuel control lever 7 in its "fuel off" position, the supply of fuel to the engine is terminated, so that without such supply the engine will come to a stop as desired.

All parts of the apparatus will then be positioned as previously described after operation of the engine in its ahead direction.

Now let it be assumed that, with the engine at rest and with the reversing piston 40 in its ahead position, in which it is shown in the drawing, the operator desires to start the engine in the astern direction. To accomplish this, the operator may move the lever 402 in slot 403 out of "stop" position to "astern" "start" position in the slot 405.

During movement of the lever 402 in the slot 403, the astern control pipe 46 and the start control pipe 400 are connected by way of the operator's control device 26 to the control supply pipe 400 and by way of communication 118 in the relay valve device 19 are therefore connected to the thirty pound supply pipe 302. Fluid under pressure from the thirty pound supply pipe 302 will then flow by way of the relay valve device 19, pipe 400, and control device 26 to the astern and start control pipes 46 and 401. Fluid under pressure thus supplied to the relay valve device 19 will cause same to disestablish its communication 118 and establish its communication 119 thereby disconnecting the control supply pipe 400 from the thirty pound supply pipe 302 and connecting said control supply pipe to the one hundred pound supply pipe 301.

Upon being connected to the one hundred pound supply pipe 301, the control supply pipe 400 will convey fluid at this higher pressure to the control device 26, whence such fluid will flow to the astern control pipe 46 and thereby to the chamber 45 in the reversing motor 11 and to the control chamber 102 in each of the relay valve devices 16 and 18 by way of the double check valve device 23 and the pipe 500.

Upon supply of fluid at one hundred pounds pressure to the chamber 45 in the reversing motor 11, the reversing piston 40 will be caused to assume its astern position opposite to that in which it is shown in the drawing to thereby position the reversing lever 3 in its corresponding position to condition the engine for operation in the astern direction. It should be pointed out, however, that as the operator's lever 402 is moved 75 in slot 403 from its "stop" position to its "astern"

"start" position, the astern control pipe will be charged with fluid at thirty pounds pressure which pressure as reflected in chamber 45 in the reversing motor 11 may either initiate movement of the reversing piston 40 or actually cause it to assume its astern position, depending upon the time which an operator may take to complete movement of said handle 402 into the slot 405. It will be understood, therefore, that the fluid at one hundred pounds pressure, if considered to be supplied initially, will effect rather rapid movement of the reversing piston 40 to its "astern" position, whereas if it is considered to be supplied subsequent to supply of thirty pound fluid after some delay, such one hundred pound fluid will either aid to complete movement of said reversing piston or act to hold said piston in its astern position once such position has been attained by virtue of the thirty pound fluid.

The relay valve device 18, too, will respond to either the thirty pound fluid or to the one hundred pound fluid to disestablish its communication 118 which connects the pipe 33 to the supply pipe 301 and to establish its communication 119 which connects said pipe 33 to the pipe 244 from the directional interlock device 17. The directional interlock device 17 at this time being in its ahead position and therefore connecting the pipe 244 to the now charged astern control pipe 46, fluid under pressure in said pipe 244 will persist to maintain the chamber 32 in the fuel cut-off cylinder device 6 charged, thereby holding the fuel control lever 7 in its "fuel off" position so that fuel may not yet be supplied to the engine.

The relay valve device 18, however, will respond only to the higher fluid pressure to disestablish its communication 118 which connects the pipe 240 to atmosphere and to establish its communication 119 which connects said pipe 240 to the supply pipe 301. It will be seen therefore that such response from the relay valve device 18 will occur only after the operator's lever 402 has been moved to a "start" position to effect supply of fluid at one hundred pounds pressure to one or the other of the ahead and astern control pipes 44, 46. With the communication 119 in the relay valve device 18 established, fluid under pressure from the supply pipe 301 will flow to the pipe 240 and thence to the directional interlock device 17 and to the control chamber 102 in the starting air valve device 15. The shoe 241 of the directional interlock device 17 will then be brought into contact with the engine crank shaft 1 to sense its direction of rotation, and the starting air valve device 15 will respond to disestablish its communication 118 which connects the pipe 503 to atmosphere and to establish its communication 119 which connects said pipe 503 to the two hundred fifty pound supply pipe 300, whereupon starting air will flow into said pipe 503 to the engine to cause same to turn over in its astern direction in accord with position of the engine reversing lever 3.

When the engine, hence its crank shaft 1, turns over in its astern direction, the directional interlock device 17 will shift from its ahead position, in which the pipe 244 is connected to the now charged astern control pipe, to its astern position in which said pipe 244 is connected to the now vented ahead control pipe 44. Fluid under pressure will then release from the chamber 32 in the fuel cut-off cylinder device 6 by way of the pipe 33, the communication 119 in the relay valve device 18, and the now vented pipe 244, whereupon, said cylinder device will respond to

move its rod 31 to its retracted position to allow the governor device to so position the fuel control lever 7 as to effect supply of fuel to the engine in amount as will effect running of said engine at its idling speed in accord with the speed setting of said governor device, it being realized that with the chamber 53 in the speed control cylinder device 12 vented to atmosphere, the governor speed control lever 5 will be in its "idling speed" position to set the governor to maintain such an engine speed.

With fuel being supplied along with the starting air which is turning the engine over in its astern direction such fuel will fire and cause running of the engine at its idling speed in the same or astern direction.

The operator may then move the operator's lever 402 out of its "astern" "start" position in the slot 405 to its opposite "astern" "run and idle" position in the slot 403 and thereby cause the start control pipe 401 to be vented to atmosphere along with the ahead and speed control pipes 44 and 54, while the astern control pipe 46 is maintained connected to the control supply pipe 400 which is charged with fluid at the one hundred pounds pressure at the time.

With the start control pipe 401 thus vented, fluid under pressure will release from the control chamber in the relay valve device 18 which will then respond to disestablish its communication 119, disconnecting the control supply pipe 400 from the one hundred pound supply pipe 301, and to establish its communication 118, thereby connecting said control supply pipe 400 to the thirty pound supply pipe 302. Pressure of fluid in the control supply pipe 400, hence the astern control pipe 46 will then reduce from one hundred pounds to thirty pounds by way of the communication 118 in the relay valve device 18, the pipe 302 and the reducing valve device 20. Pressure of fluid in the control chamber 102 in the relay valve device 18 will reduce from one hundred pounds to thirty pounds by way of the pipe 500, the double check valve device 23 and the astern control pipe 46. The relay valve device 18 will then respond to disestablish its communication 119 which connects the pipe 240 to the one hundred pound supply pipe 301 and to establish its communication 118 which connects said pipe 240 to atmosphere, thereby allowing release of fluid under pressure from the directional interlock device 17 with consequent retraction of its shoe 241 and from the control chamber in the starting air valve device 15 which will respond to disconnect the pipe 503 from the supply pipe 300 and to vent said pipe 503 to atmosphere. Starting air is thus cut off to the engine, which will continue to run in astern direction on fuel.

It will be appreciated that at the time that the pressure of fluid in the astern control pipe 46 is reduced from one hundred pounds to thirty pounds as above, such reduction will also be effected in the chamber 45 in the reversing motor 11 as well as in the control chamber in the relay valve device 16 with no effect on the position of either.

With the engine running on fuel in its astern direction, the speed of the engine may be regulated by proper adjustment of position of the operator's control lever 402 between "astern" "run and idle" and "astern" "full speed" positions.

To summarize, to start the engine for operation in its astern direction after previous operation in its ahead direction, the operator may simply move the operator's control lever 402 from its

"stop" position to its "astern" "start" position, and by virtue of resultant positioning of the relay valve device 19, effecting supply of one hundred pound fluid to the astern control pipe 46, causing shift of the reversing piston 40 to its astern position to condition the engine for operation in that direction, causing the relay valve device 16 to connect the chamber 32 in the fuel cut-off cylinder device 6 to the now charged pipe 244 from the directional interlock device 17 so that the fuel control lever 7 will be maintained in its "fuel off" position until the shaft 1 begins to rotate in its proper direction, and causing the relay valve device 18 to connect the pipe 240 to the one hundred pound supply pipe 301 for effecting engagement of the directional interlock shoe 241 with shaft 1 and for causing the starting air valve device 15 to connect the pipe 503 to the two hundred and fifty pound supply pipe 300 for supplying starting air to the engine to turn same over in its astern direction. As soon as the engine turns over in its astern direction on starting air, the directional interlock device 17 will assume its astern position, connecting the pipe 244, hence venting the chamber 32 in the fuel cut-off cylinder device 6, to the now vented ahead control pipe 44 to allow the governor device to move the fuel control lever 7 out of its "fuel off" position for supplying fuel to the engine. When the engine thus being turned over on starting air begins to run on fuel, the operator may move the operator's lever from its "astern" "start" position in slot 405 to its opposite "astern" "run and idle" position in the slot 403, thereby effecting reduction in pressure in the astern control pipe 46 from one hundred pounds to thirty pounds by virtue of a shift in position of the relay valve device 19 and the reducing valve device 20. The reduction in pressure in the astern control pipe 46 to thirty pounds causes the relay valve device 18 to effect venting of the pipe 240 to atmosphere, with consequent retraction of the directional interlock shoe 241 to a position out of contact with the shaft 1 and conditioning of the starting air valve device 15 to effect termination of supply of starting air to the engine via the pipe 503 which is at same time vented to atmosphere. The operator may then regulate the speed of the engine by positioning the operator's lever between the "astern" "run and idle" and "astern" "full speed" positions according to the speed desired.

While the engine is thus operating in its astern direction, if the operator should desire to effect a "snap" reversal of the engine, he may move the operator's lever 402 in slot 403 from its "astern" position to its "ahead" "start" position in the slot 404, thereby effecting connection of the ahead and start control pipes 44 and 401 to the control supply pipe 400 while at the same time venting the astern and speed control pipes 46 and 54 to atmosphere.

Upon connection of the ahead control pipe 44 to the control supply pipe 400, fluid under pressure from the latter will flow via the former, the directional interlock device 17 in its astern position, the pipe 244, communication 119 in the relay valve device 16 which maintains such communication established by virtue of its control chamber remaining pressurized by the fluid under pressure in the ahead control pipe, and the pipe 33 to the chamber 32 in the fuel cut-off cylinder device 6 to cause the piston 30 to move the fuel control shaft 7 to its "fuel off" position so that the engine might coast to a stop. At the same

time the fluid at thirty pounds pressure will flow via the ahead control pipe to the chamber 43 in the reversing motor 10 to cause same to shift to its ahead position in which it is shown in the drawing to condition the engine for operation in its ahead direction. Fluid at the thirty pounds pressure will also be maintained in the control chamber of the relay valve device 18, as will be appreciated from previous description, and said device will remain positioned for venting the pipe 240 to atmosphere. At the same time, fluid at the thirty pound pressure will flow via the start control pipe 401 to the control chamber in the relay valve device 19 which will then respond to disestablish connection between the control supply pipe 400 and the thirty pound supply pipe 302 and to establish connection between said control supply pipe and the one hundred pound supply pipe 301. With the control supply pipe 400 charged with fluid at one hundred pounds, pressure of fluid in the ahead control pipe 44 and consequently in the control chamber in the relay valve device 18 will be increased from thirty to one hundred pounds, causing said relay valve device to connect the pipe 240 to the supply pipe 301, thereby effecting supply of fluid under pressure to the directional interlock device 17 to cause engagement of its shoe 241 with the engine crank shaft 1 and to the control chamber in starting air valve device 15, causing same to establish its communication 119 connecting the pipe 503 to the pipe 300 for effecting supply of starting air to the engine to turn same over in its ahead direction.

Once the engine begins to turn in its new or ahead direction, the directional interlock device 17 will shift from its astern to its ahead position, thereby disconnecting the pipe 244 from the now charged ahead control pipe 44 and connecting said pipe 244 to the now vented astern control pipe 46. Fluid under pressure will then release from the chamber 32 in the fuel cut-off cylinder device 6 which will then respond to move its rod 31 to its retracted position disposed away from the fuel control lever 7 so that the speed governor device may position said lever to effect supply of fuel to the engine.

When the engine begins to run on fuel, the operator may then move the operator's control lever 402 from its "ahead" "start" position in the slot 404 to its opposite "ahead" "run and idle" position in the slot 403, thereby effecting venting of fluid under pressure from the start control pipe 401, while maintaining the ahead control pipe 44 connected to the control supply pipe 400 and the astern and speed control pipes 46 and 54 vented to atmosphere. Upon thus venting the start control pipe 401, fluid under pressure will release from the control chamber in the relay valve device 19, causing same to assume its position for disestablishing its communication 119 and establishing its communication 118, thereby disconnecting the control supply pipe 400 from the one hundred pound supply pipe 301 and connecting said control supply pipe to the thirty pound supply pipe 302 for reducing the pressure of fluid in the control chamber in the starting air valve device 15, which responds thereto to terminate supply of starting air to the engine, as will be appreciated from previous description.

By movement of the operator's lever 402 between "ahead" "run and idle" and "ahead" "full speed" positions, the operator may regulate the speed of the engine as desired.

Should the operator then desire to stop the

engine, he may move the operator's control lever 402 in slot 403 to "stop" position, thereby effecting venting of the ahead control pipe 44 and speed control pipe 54 to atmosphere along with the astern and start control pipes 46 and 401. Upon venting of the ahead control pipe to atmosphere, fluid under pressure from the control chamber in the relay valve device 16 will release via pipe 500 and double check valve device 23, so that said relay valve device will respond to disestablish its communication 119 and to establish its communication 118, thereby disconnecting the pipe 33 from the pipe 244 and connecting said pipe 33 to the supply pipe 301. Fluid under pressure will then flow via communication 118 in the relay valve device 16 and the pipe 33 to the chamber 32 in the fuel cut-off cylinder device 6 to cause the rod 31 to move the fuel control lever 7 to its "fuel off" position to terminate supply of fuel to the engine, allowing same to coast to a stop. Other parts of the apparatus will be in the respective positions in which they are shown in the drawing and described previously.

It should be appreciated that while a "snap" reversal of the direction of operation of the engine from astern to ahead has been described, it will be seen that in similar fashion a "snap" reversal of the engine may be effected while same is operating in its ahead direction.

Summary

It will now be seen that I have provided a relatively simple engine control apparatus for controlling the starting, running, reversing and stopping of a reversible Diesel engine.

In the control apparatus disclosed herein, the operator's control device 26, the relay valve device 19, and the reducing valve device 20 may be located at a station remote from the engine, such as the pilot house on a ship which is to be controlled remotely. By virtue of such an arrangement as the present invention affords, the start control pipe 401 need not extend from the operator's control device 26 in the pilot house back to the engine to control supply of starting air, as is usually the arrangement, but rather need only extend to the relay valve device 19 which operates to increase and decrease pressure of fluid in the control supply pipe 400 for effecting control of starting air supply, thus conserving pipe or tubing and the time required to install same.

Having now described our invention, what we claim as new and desire to secure by Letters Patent is:

1. Apparatus for controlling starting, running, and stopping of an internal combustion engine comprising in combination, a first source of fluid at one pressure, a second source of fluid at another and higher pressure than said one pressure, a control supply pipe, an ahead control pipe, a start control pipe, an operator's control device having a start position in which said ahead control pipe and said start control pipe are connected to said control supply pipe, a run position in which said start control pipe is vented to atmosphere and said ahead control pipe is connected to said control supply pipe, and a stop position in which both said ahead control pipe and said start control pipe are vented to atmosphere, a first relay valve device which connects said control supply pipe to said first source when said start control pipe is vented to atmosphere and connects said control supply pipe to said second source when said start control pipe is pressurized, a fuel cut-off motor operable by

pressure of fluid supplied to a chamber to effect cut off of fuel to the engine and to terminate operation upon release of fluid under pressure from said chamber, a second relay valve device operable upon supply of fluid to said ahead control pipe at said one or said other pressure to connect said chamber to atmosphere and upon venting of said ahead control pipe to atmosphere to effect supply of fluid under pressure to said chamber, a starting air valve device responsive to pressurization of a control chamber to effect supply of starting air to said engine and upon venting of said control chamber to atmosphere to terminate such supply, and a third relay valve device responsive to supply of fluid at said other pressure to said ahead control pipe to effect supply of fluid under pressure to said control chamber and upon reduction in pressure of fluid in said ahead control pipe to or below said one pressure to vent said control chamber to atmosphere.

2. Apparatus for controlling starting, running, stopping and reversing of a reversible internal combustion engine operable by fuel supplied thereto comprising in combination, a first source of fluid at one pressure, a second source of fluid at another and higher pressure than said first source, a source of starting air, a first control pipe, a second control pipe, fluid pressure reversing means operable upon supply of fluid under pressure to said first control pipe and venting of fluid under pressure from said second control pipe to a reversing position to condition said engine for operation in a reverse direction, fuel cut-off motor means operable upon supply of fluid under pressure to a pressure chamber to prevent fuel supply to said engine and upon release of fluid under pressure from said pressure chamber to allow fuel to be supplied to said engine, starting air control means responsive to supply of fluid under pressure to a first control chamber to effect supply of starting air to said engine and responsive to release of fluid under pressure from said first control chamber to terminate such supply of starting air, a double check valve having one inlet opening connected to said first control pipe, a second inlet opening connected to said second control pipe, and an outlet opening, a directional control pipe, first relay valve means responsive to supply of fluid at said one pressure to a second control chamber connected to said outlet opening to establish connection between said pressure chamber and said directional control pipe and responsive to release of such fluid from said second control chamber to establish connection between said pressure chamber and said second source of fluid, directional interlock means responsive to turning of said engine in its reverse direction to disestablish connection between said directional control pipe and said second control pipe and to establish connection between said directional control pipe and said first control pipe, a second relay valve device having a third control chamber connected to said outlet opening and responsive to supply thereto of fluid at said other pressure to establish connection between said first control chamber and said second source of fluid and responsive to reduction in pressure of fluid in said third control chamber to establish connection between said first control chamber and atmosphere, a third control pipe, a control supply pipe, a third relay valve device having a fourth control chamber connected to said third control pipe and responsive to supply of fluid at said one pressure to establish connection between said control sup-

ply pipe and said second source of fluid and responsive to release of fluid under pressure from said fourth control chamber to establish connection between said control supply pipe and said first source of fluid, an operator's control device operable to a position to establish connection between said control supply pipe, said second control pipe and said third control pipe while connecting said first control pipe to atmosphere and to a second position to connect said third control pipe to atmosphere while maintaining said second control pipe connected to said control supply pipe, and means for maintaining said one pressure in said first source of fluid.

3. Apparatus for controlling the starting, running and stopping of an internal combustion engine, comprising an ahead control pipe, a start control pipe, a control supply pipe, fuel cut-off motor means operable to effect cut off of fuel supply to the engine, starting means operable to effect starting of said engine, motor control means responsive to establishment of one pressure of fluid in said ahead control pipe to effect operation of said fuel cut-off motor means and responsive to venting of said ahead control pipe to atmosphere to terminate operation of said fuel cut-off motor, starting control means responsive to establishment in said ahead control pipe of another pressure higher than said one pressure to effect operation of said starting means, means responsive to establishment of at least said one pressure in said start control pipe to effect establishment of said other pressure in said control supply pipe and to venting of said start control pipe to atmosphere to effect establishment of said one pressure in said control supply pipe, and operator's control means operable to a start position to establish connection between said control supply pipe, said ahead control pipe and said start control pipe, to a run position to effect venting of said start control pipe to atmosphere while maintaining said ahead control pipe connected to said start control pipe and to a stop position to effect venting of both said ahead control pipe and said start control pipe to atmosphere.

4. Apparatus for controlling starting, running and stopping of a reversible internal combustion engine comprising, in combination, engine reversing means operable by fluid at a chosen pressure, ahead and astern pipes for conveying fluid under pressure to and from said reversing means for controlling operation thereof, engine fuel cut-

off means, cut-off control means responsive to pressure of fluid less than said chosen pressure to effect operation of said cut-off means, directional control means for sensing direction of operation of said engine according to the one of said pipes supplied with fluid under pressure and cooperative with said cut-off control means when subject to pressure of fluid at or exceeding said chosen pressure to also effect operation of said cut-off means only with said engine turning contrary to operation of said reversing means, starting means operable only in response to pressure of fluid exceeding said chosen pressure, means for selectively opening said cut-off control means and starting means to the one of said pipes supplied with fluid at the higher pressure, and an operator's control device for selectively supplying fluid to either one of said pipes at either one of the above mentioned pressures while venting the other pipes.

5. Apparatus for controlling starting, running and stopping of a reversible engine having a part rotatable in a direction corresponding to the direction of operation of said engine, comprising in combination with said part, ahead and astern pipes, means including an operator's control valve device for selectively providing fluid in either one of pipes at either of two different pressures while venting the other of said pipes, engine reversing means movable in response to the lower of the two pressures of fluid providable in either one of said pipes to a corresponding position, fuel cut-off means, cut-off control means responsive to pressure of fluid lower than said lower pressure to effect operation of said cut-off means, directional means responsive to direction of operation of said part cooperative with said cut-off control means when subject to pressure of fluid at and exceeding said lower pressure to also effect operation of said cut-off means except with said part turning in a direction corresponding to the position of said reversing means, engine starting means responsive only to the higher one of said two pressures of fluid, and means controlled by the pressures of fluid in said pipes for selectively connecting said cut-off control means and starting means to the one of said pipes supplied with fluid under pressure.
